US00D547736S

(12) **United States Design Patent** (10) **Patent No.:** **US D547,736 S**
(45) **Date of Patent:** **** Jul. 31, 2007**

(54) **LIGHT EMITTING DIODE**

(75) Inventor: **Kazuhiko Kamada**, Tokushima-ken (JP)

(73) Assignee: **Nichia Corporation**, Anan (JP)

(**) Term: **14 Years**

(21) Appl. No.: **29/267,973**

(22) Filed: **Oct. 26, 2006**
